HANDBAG LOCK PLATE

David Damast, 22-14 40th Ave.,
Long Island City, N.Y. 11101

Filed Feb. 6, 1967, Ser. No. 5,700

Term of patent 3½ years

(Cl. D87-2)

Fig. 1.

Fig. 2.

Fig. 3.

FIG. 1 is a perspective view of a handbag lock plate showing my new design wherein the exterior is rectangular in configuration,

FIG. 2 is a top edge view thereof,

FIG. 3 is a front elevational view thereof,

FIG. 4 is a perspective view of a handbag lock plate showing an embodiment of my new design wherein the exterior is circular in configuration,

FIG. 5 is a front elevational view thereof,

FIG. 6 is a side elevational view thereof,

FIG. 7 is a perspective view of a handbag lock plate showing a further embodiment of my new design wherein the exterior is elliptical in configuration.

FIG. 8 is a front elevational view thereof, and

FIG. 9 is a side elevational view thereof.

The rear views of the various forms of handbag lock plate are similar without the surface ornamentation.

I claim:

The ornamental design for a handbag lock plate, substantially as shown and described.
